(57) **CLAIM**

The ornamental design for a dental detection device, as shown and described.

DESCRIPTION

FIG. 1 is a top view of the dental detection device;
FIG. 2 is a left side view thereof;
FIG. 3 is a front thereof;
FIG. 4 is a bottom view thereof;
FIG. 5 is a right side view thereof;
FIG. 6 is a back view thereof; and,
FIG. 7 is a top, front, and right side perspective view thereof. The broken lines in FIGS. 3 and 7 depict portions of the article that form no part of the claimed design.
